UNITED STATES PATENT OFFICE.

HARRY THAYER KINGSBURY, OF KEENE, NEW HAMPSHIRE.

DESIGN FOR A TOY-CAR BOTTOM PLATE.

SPECIFICATION forming part of Design No. 30,157, dated February 7, 1899.

Application filed January 13, 1899. Serial No. 702,111. Term of patent 7 years.

To all whom it may concern:

Be it known that I, HARRY THAYER KINGSBURY, a citizen of the United States, residing at Keene, in the county of Cheshire, State of New Hampshire, have invented a certain new and useful Design for a Toy-Car Bottom Plate, of which the following is a description, reference being had to the accompanying drawings and to the letters and figures of reference marked thereon.

My invention is a new and original design for the bottoms of toy-car bodies; and the leading feature thereof consists of a toy-car body bottom of the shape and configuration herewith set up, and illustrated in the accompanying drawings, in which—

Figure 1 is a top plan view, Fig. 2 is an end view, and Fig. 3 is a side elevation, of a toy-car bottom plate embodying my design.

In the drawings the main portion of the bottom plate is shown as a flat piece A, which is continuous from the points *a* to *b*, except for the curved projections 1 2 adjacent either

end and the central projecting part 3. Outside the points *a* *b* the flat piece is formed with downwardly-inclined pieces *c* *d*, curved, as shown, into a step-like resemblance, while the extreme ends of the flat piece A are turned upwardly to form vertically-projecting pieces *e*.

The essential feature of the design is the bottom plate with the downwardly-projecting step-like-formed parts *c* *d*, to which may be added the upwardly-turned parts *e*.

Having thus described my invention, what I claim, and desire to secure by Letters Patent, is—

The design for a toy-car bottom plate, substantially as shown and described.

In testimony whereof I affix my signature in presence of two witnesses.

HARRY THAYER KINGSBURY.
